BROACHING MACHINE FOR STUB
BALL JOINTS

William A. Hart, Detroit, Mich., assignor to
Colonial Broach Company, a corporation of
Michigan

Application September 10, 1931, Serial No. 562,012

8 Claims. (Cl. 90—33)

This invention relates to broaching machines and particularly to a broaching machine for supporting a work piece in such manner as to have a cylindrical aperture in the supported end enlarged and slotted by the passage of a broaching cutter thereacross.

The main objects of my invention are: to provide a broaching machine with a head for receiving and supporting a yoked work piece in position to have a broaching cutter machine a slot in the ends thereof and finish the surface of an aperture provided therein by a single passage of the cutter; to provide centers for supporting the body portion of the yoke in such manner as to have the yoke span one of the centers the body portion of which is hollow to permit the passage of a cutter across the ends of the yoke; to provide a wedge member for engaging the side of one branch of the yoke in the direction in which the cutter is moved for bracing the yoke and relieving the center from the strain to which it would otherwise be subjected when the cutter is drawn thereacross; to rotatably mount a head, having a splined end for supporting the yoke, in such manner as to revolve the extending yoke portions into a position to span bracing blocks during the time they are being broached; to provide a lock for the splined supporting member which accurately aligns the yoke relatively to the broach and which is automatically unlatched at the end of the broaching operation to permit the splined end to be revolved so that the finished yoke may be removed and a new yoke supported thereon; and to provide interconnecting means for a plurality of the yoke supports which are actuated to opposite positions each time a control handle is moved to enable a single operator to change the yoke on one support during the time the yoke on the other support is being machined.

Other objects and features of novelty of my invention will be either specifically pointed out or will become apparent when referring, for a better understanding of my invention, to the following description in conjunction with the accompanying drawings, wherein:

Figure 1 is a broken plan view, partly in section, of a broaching machine embodying features of my invention.

Fig. 2 is a sectional view of the structure illustrated in Fig. 1, taken on the line 2—2 thereof,

Fig. 3 is a sectional view of the structure illustrated in Fig. 1, taken on the line 3—3 thereof,

Fig. 4 is a reduced end view of the structure illustrated in Fig. 1,

Fig. 5 is a view, in elevation, of a modified form

of a supporting head for a broaching machine embodying features of my invention,

Fig. 6 is an enlarged view of one of the work supporting heads illustrated in Fig. 5,

Fig. 7 is a plan view, partly in section, of the structure illustrated in Fig. 6,

Fig. 8 is an end view of the structure illustrated in Fig. 6,

Fig. 9 is a sectional view of the structure illustrated in Fig. 7, taken on the line 9—9 thereof, 10

Fig. 10 is a sectional view of the structure illustrated in Fig. 7, taken on the line 10—10 thereof,

Fig. 11 is a front view of a work piece in the nature of a stub ball yoke which is supported on the fixture illustrated in Fig. 6, and 15

Fig. 12 is a side view of the structure illustrated in Fig. 11.

The stub ball yoke referred to hereinabove, is illustrated in Figs. 11 and 12 as comprising a body portion 15 which projects laterally, at 16, and longitudinally at each end of the laterally extending portion, at 17, to form a yoke having cylindrical apertures 18 which are opened at the top ends through the medium of slots 19. The body portion 15 is provided with a splined aperture 21, 25 as illustrated in Fig. 11, for effecting the attachment of the stub ball yoke to the propeller shaft of an automotive vehicle. A similar yoke is disposed at right angles to the yoke 14 above referred to, the two yokes being joined through the medium of apertures 18 thereof to a centrally disposed shafted ball for effecting a universal joint in the propeller housing to permit the flexing of the housing during the operation of the vehicle. 30

Referring to Fig. 4, I have illustrated one form 35 of supporting fixture for the stub ball yoke which is to have the surface of the aperture 18 machined to predetermined dimensions by a broaching cutter. I have provided a casting 23 having a machined surface 24 and a cylindrical hollow 40 flange 25 by which the casting 23 is attached to a face plate of a broaching machine, as shown in the figure. The broaching cutter 26 extends through the hollow flange 25 and is guided by the rail members 27 and 28, illustrated in Fig. 3, 45 which are attached to a plate 29 by bolts 31 which plate is supported on the extending portion 32 of the casting 23 by bolts 33. An oil cup 34 is mounted on the rail 28 and is connected by an orifice 35 to an oil groove 36 which extends 50 from the inner surface of the rail 28 across the face of the plate 29 to the inner surface of the rails 27 to effect the lubrication of all sides of the broaching cutter.

Spanning the central portion of the rails 27 55

and 28, I have provided a bridging member 37 having a center 38 for engaging a central recess in the body portion 15 of the stub ball yoke 14, before the central splined aperture 21 is cut 5 therein. Supporting and engaging blocks 39 are mounted on the ends of the bridging member 37 through which bolts 40 extend for retaining the blocks 39 and the bridging member 37 in fixed relation to the rails 27 and 28. When the stub ball yoke 14 is positioned to have its central recess engaged by the center 38, the extending ends 17 of the yoke span the bridging member 37 while the sides of the laterally extending portion 16 thereof are engaged by the inner surface of the 10 engaging blocks 39 to have the yoke supported on four sides against rotational movement.

The bridging member 37 is provided with a recess 41 which is slightly larger than the finished aperture 18 in the extending ends 17, for permitting 15 the passage of the cutting blades 42 and 43 of the broaching cutter 26 therethrough, for machining the aperture and the slot to predetermined dimensions during one passage of the cutter across the yoke. A V-shaped block 44 20 is spaced from the bridging member 37 in predetermined relation to the center 38, for engaging and supporting the body portion 15 of the yoke.

Adjacent to the V-shaped block 44, I have 25 provided an adjustable center 45 which is mounted on a boss 46 of the casting 23 as illustrated more clearly in Fig. 3. The boss 46 has a chamber 47 for receiving an enlarged end 48 of the center 45 and also for receiving a spring 30 49 which biases the center 45 away from the center 38. A cam 51 is mounted on a shaft 52 which is supported in bosses 53 of the casting 23 for effecting the positioning of the center 45 relative to the center 38 for accurately centering 35 the stub ball yoke on the fixture. A suitable handle 54 is attached to an extending portion of the shaft 52 for effecting the actuation of the shaft and also the cam 51.

On the opposite end of the shaft 52 from that 40 supporting the handle 54, I have provided an eccentric arm 55, on the end of which a plunger 56 is pivotally supported by a pivot 57 upon which it is retained by a nut 58. A head 59 is provided on the opposite end of the plunger 56 and is 45 engageable with a member 61 which is screwed into a slideable wedging member 62 for the purpose of withdrawing the wedging member when the shaft 52 is rotated to a predetermined position. The wedging member 62 is biased toward 50 the broaching cutter 26 by a spring 63 to have the sloping wedging surface 64 thereof engage the outer surface of one of the yoke extensions 17, as illustrated in Fig. 1, for the purpose of relieving the center 38 and the bridging member 55 37 from the strain to which it would be otherwise subjected if the wedging member 64 were not employed.

Referring to Fig. 2, the wedging member 62 60 is illustrated as being provided with a flat portion 66 having projecting flanges 67 which register with the guide plate 68 and is retained thereon by the side extending members 69 which are supported on the plate 68 by bolts 71. The guiding plate 68 is retained by suitable bolts 72 on a 65 supporting plate 73 which is mounted on the casting 23 by a bolt 74.

When it is desired to mount a stub ball yoke 70 in the fixture illustrated in Figs. 1 to 4 inclusive, the handle 54 is rotated in a counter clockwise 75 direction for effecting a similar rotation to the

cam 51 which releases the center 45 to permit the spring 49 thereof to bias the center rearwardly to increase the span between the centers 38 and 45. The stub ball yoke 14 has two recesses in the nature of centers provided in the ends of the body portion 15 and has the inner surface of the extending flanges 16 and the yoke portions 17 machined with holes 18 of reduced diameter drilled therethrough. The center recess in the end of the body portion 15 is positioned over the center 38 with the yoke extensions 17 bridging the member 37 and the body portion 15 resting in the V-block 44. The handle is then turned in a clockwise direction to move the center 45 forwardly into tight clamping relation with the center recess on the opposite end of the body portion 15. The cam acts as a lock for retaining the yoke in clamped position relative to the bridging member 37.

When the handle was first revolved in a counter clockwise direction the head 59 of the plunger 56 engaged the member 61 to withdraw the sloping surface 64 of the wedging member 62, against the bias of the spring 63, out of engagement with the stub ball yoke 14 to permit the removal of the yoke from the fixture. As the stub ball yoke is being mounted in the fixture, the clockwise rotation of the handle 54 moves the head 59 out of engagement with the member 61 to permit the spring 63 to bias the wedging member 62 to have the wedging surface 64 thereof wedge the yoke between the bridging member 37 and the guiding plate 68 on the side of the fixture in the direction in which the broaching cutter 26 is moved.

It is to be understood that, before the yoke is so mounted in the fixture, the broaching cutter 26 is reciprocated from the position illustrated in Fig. 1 to the opposite side of the fixture in a position to cut the notch 19 and dress the aperture 18 therein. From Fig. 1 it will be noted that the broaching cutters 43 are mounted ahead of the cylindrical broaching cutters 42, for the purpose of first machining the slot 19 of predetermined width in the end of the yoke 17 and thereafter to have the cylindrical portion of the broach 40 dress the sides of the aperture 18 into predetermined finished dimensions.

In Fig. 4 I have illustrated the passage of the broaching cutter 26 through the fixture during 45 the machining of the slot 19 and the aperture 18 in the yoke 14 supported therein. It is to be understood that the broaching cutter 26 is reciprocated by a pull rod 75 which is a part of a ram (not illustrated).

In Figs. 5 to 10 inclusive, I have illustrated a modified form of fixture for supporting a stub ball joint 14 in which a splined central hole 21 is provided in the body portion 15 thereof. In the enlarged views of Figs. 6, 7 and 8, I have illustrated the fixture which includes a casting 77 having a hollow positioning flange 78 and supported on the face plate 79 by bolts 81, as illustrated in Fig. 5. A spaced arm 82 extends frontwardly of the casting having a boss 83 on the end thereof in which a bearing 84 is provided in aligned relation to a bearing 85 mounted in the casting. A shaft 86 is journaled in the bearings, its central portion, between the casting and the boss 83, supporting the block 87 which is rigidly attached thereto by screws 88 to rotate with the shaft. A recess 89 is provided on the side of the block 87 facing toward the broaching cutter 91, in which a cylindrical end 92, of a ball yoke supporting member 93, is pressed for retaining the member 75

93 in extension of the block 87. The opposite end of the member 93 is provided with a splined cylindrical portion 94 upon which the stub ball yoke 14 is mountable, as illustrated in dot and dash lines in Figs. 6 and 7.

The casting 77 has a laterally extending portion 95 in which a plate 96 and side rail members 97 and 98 are supported by bolts 99, as illustrated in Fig. 6, for the purpose of forming a guide for the broaching cutter 91. The cutter 91 is substantially similar to the cutter 26 referred to above, in reference to Figs. 1 to 4, and is reciprocated in the same manner by a suitable ram for moving the cutter 91 longitudinally in the guide 15 through the flange 78. Suitable blocks 101 are positioned on either side of the path, through which the broaching cutters 91 traverse, which are spanned by the yoke portion 17 of the ball yoke 14, for the purpose of guiding and rigidly retaining the yoke in predetermined position relative to the cutter 91.

For further supporting the block 87 against lateral movement relative to the shaft 86, I have provided a positioning bar 102 supported in the outer side thereof by bolts 103 and have provided a notch 104 in the inner side thereof which is in contiguous relation to the outer surface of a sleeve 105 positioned in the casting 77. The sleeve is provided with an inwardly directed flange 106 for supporting one end of a spring 107, the outer end of which engages the enlarged end portion 108 of a positioning pin 109 which is biased thereby outwardly from the sleeve 105. An aperture 111 is accurately positioned in the side of the slot 104, in which the head 108 of the pin 109 registers, when the block 87 is in predetermined position to have the stub ball yoke 14 accurately positioned relative to the broaching cutter 91. A V-shaped block 112, as illustrated in Fig. 6, is mounted on the arm 82 of the casting having the surface 113 thereof horizontally disposed to assist in accurately positioning the yoke relative to the cutter. In a like manner the stop member 112 has a surface 114 which limits the rotation of the block 87 in the opposite direction into a position where a machined stub ball yoke may be removed from the splined end 94 of the supporting member 93 and a new yoke 14 placed thereon.

For unlatching the block 87, after the stub ball yoke 14 has been machined, I have employed a plunger 115 which is cylindrical in shape and provided with a square extending portion 116 which is tapered on one side at 117 and extending through a slot 118 provided in the pin 109. A recess is provided in the casting 77 at 119 and a similar recess is provided in the side of the plunger 115 wherein a spring 120 is retained for positioning the plunger relative to the casting. A plate 121 is supported by screws 122 on the back surface of the casting 77 for enclosing the aperture which encases the plunger 115.

For actuating the plunger 115 relative to the position of the broach 91, I have mounted a block 123 on the base of the broaching cutter 91, as illustrated in Figs. 6 and 7. The block has a sloping surface 124 which engages the rounded end 125 of the plunger 115, after the broaching cutter 91 has completely passed through the ball yoke. The sloping surface 124 moves the plunger 115 longitudinally to have the sloping surface 117 thereof move through the slot 118 in the plunger 109, for moving the plunger laterally to withdraw it from the aperture 111 provided in the block 87. The withdrawal of the plunger from the aperture frees the block 87 from the casting

77 and permits its rotation between the limits of the stop surfaces 113 and 114.

For effecting the operation of both of the fixtures illustrated in Fig. 5, I have provided straps 127 which are supported on the outermost surface of the blocks 87, having handles 128 on their upper ends and bosses 129 on their lower ends. A connecting rod 131 joins the two bosses 129 for effecting the opposite rotation of both of the blocks 87 when one of the handles 128 is actuated. When one block is clamped in horizontal position the other block will be retained at an angle, as illustrated in Fig. 5, to have one fixture positioned so as to effect machining of a yoke 14, while a machined yoke is being removed from the opposite fixture and a new yoke placed thereon.

During the machining of the one yoke, the ram of the opposite fixture is being reciprocated to move the broaching cutter to its frontwardmost position at the time the broaching cutter has passed beyond the yoke in the opposite fixture. At the end of the broach travel the block 87 of the finished yoke is unlatched so that, upon the actuation of one of the handles 28, the yoke 25 will move out of the machinable position to a position in which it may be removed from the block as the yoke on the opposite block is moved into machinable position and latched.

While I have described and illustrated but two embodiments of my invention, it will be apparent to those skilled in the art that various changes, omissions, additions, and substitutions may be made therein without departing from the spirit and scope of my invention as set forth in the accompanying claims.

I claim as my invention:

1. A broaching machine having a broaching cutter for machining the ends of the yoke portions of a member, including, a center for receiving one end of the body portion of the member, and having a slot in its body portion through which said broach extends, an adjustable center for engaging the opposite end of the body portion of said member for positioning it in the fixture, a wedge member extending between one side of one of the yoke portions of the member and the wall of the fixture, and control means for actuating said adjustable center to retracted position including means for withdrawing the wedge from between the side of the yoke portion and the fixture wall.

2. A broaching machine having a broaching cutter for machining the ends of yoke portions of a member including, in combination, a center having a slot in its body portion through which said broach extends for receiving a center recess in one end of the body portion of said member, an adjustable center for engaging the opposite end of said body portion for positioning the member in the fixture, a wedge member extending between one side of one of the yoke portions of the member and the wall of the fixture on the side toward which the broaching cutter is moved during the cutting operation, a cam for actuating the adjustable center, an eccentric for controlling the position of the wedge member, and a shaft upon which said cam and eccentric are mounted in fixed position for effecting the retrieving of the center and the wedge member when the shaft is rotated in one direction and for effecting their movement into clamping position when rotated in the opposite direction.

3. A broaching machine for machining a member having a body portion and spaced projecting

arms, broaching means, means spanned by said arms and engaging one end of said body portion, said means being provided with an aperture over the ends of which the arms extend and through which said broach is movable, and means for releasably engaging and supporting the other end of said body portion.

4. A broaching machine for machining a member having a body portion and spaced projecting arms, a broach, means provided with an aperture over which said arms extend and through which said broach is movable, and means for releasably engaging and supporting said body portion.

5. A broaching machine for machining a member having a body portion and spaced projecting arms, means spanned by said arms and having a projecting center engageable with one end of said body portion, and an adjustable center engageable with the opposite end of said body portion, said means having an aperture over which said arms extend and through which said broach is movable to machine said arms.

6. A broaching machine for machining a member having a body portion and spaced projecting arms, means spanned by said arms and having a projecting center engageable with one end of said body portion, an adjustable center engageable with the opposite end of said body portion, said means having an aperture through which said

broach is movable and over the ends of which said arms extend, and movable means engageable with said member for bracing said member to resist the force of the broach during a cutting stroke.

7. A broaching machine having a broaching cutter for machining the ends of the yoke portions of a member including, in combination, an element straddled by said yoke portion and having a recess in its body portion over which the arms of the yoke portion extend and through which said broaching cutter is movable, means for engaging said member, and a wedge movable between one side of the yoke portion of the member and the wall of the fixture on the side toward which the broaching cutter is moved during a cutting stroke.

8. A broaching machine having a broaching cutter for machining the ends of a yoke portion of a member including, in combination, an element straddled by said yoke portion having a recess over which the arms of said yoke portion extend, a broaching cutter movable through said recess and engaging said arms, and means for bracing the yoke portion on the side toward which the broaching cutter is movable during a cutting stroke.

WILLIAM A. HART.
